UNITED STATES PATENT OFFICE.

CLIFFORD M. WATROUS, OF EAST HAMPTON, CONNECTICUT, ASSIGNOR TO GONG BELL MANUFACTURING COMPANY, OF EAST HAMPTON, CONNECTICUT, A CORPORATION OF CONNECTICUT.

TOY WHEEL.

Application filed May 8, 1924. Serial No. 711,825.

This invention relates particularly to toys and more especially to wheels for toys of the type commonly known as rolling toys. It pertains essentially to a wheel which it is possible to produce at a low cost with a minimum of scrap waste.

Such wheels are used in various forms and designs on toys, to simulate in appearance, types of wheels which are used in ordinary commercial vehicles of various sorts, and the designs may even be modified to give the appearance, of the so called pneumatic type of tire, where there is a comparatively large tread portion, which may be, in some instances, covered with a resilient material in simulation of a pneumatic tire.

The main object, of the present invention, is to provide uniformity in production at a minimum cost and loss of scrap, and at the same time, produce a wheel, of unusually attractive appearance, which may be made to simulate any desired standard type of wheel such as are employed on trucks, pleasure vehicles, motor cycles and the like.

It is a further object to produce a wheel from a comparatively thin material which will have unusual strength and durability and at the same time, afford production of a great uniformity and accuracy, both as to the running or tread portions of the wheels and the centering or axle portions thereof.

It has long been a practice in the manufacture of toys to use cast wheels and difficulties have been encountered in securing economical and uniform production. Small cast wheels are more or less fragile, break easily under sharp blows, and vibration, and require numerous operations in manufacture to secure true running wheels with smooth running treads. For instance, with cast wheels, and in fact, with such formed wheels as have been heretofore known to applicant, there must be a truing up operation to secure smooth running.

Difficulties in assembly, which is an important factor of economical toy manufacturing, are improved with the wheel herein described, as when it comes from the dies, it is properly centered and trued and requires no machining, grinding or tumbling.

In contradistinction to this, the cast type must be trued up, and centered, and even machined or reamed, to give a proper fit for the axle, and ground or turned, as to the periph-

eral edge, to give a proper tread. The usual custom is to tumble wheels to remove the sharp "sprues" and rough edges. The wheels must then be bored and reamed for the axle, and the peripheral edges, for the tread, must be ground or turned to center with the axle opening.

The wheel hereinafter disclosed is centered; its tread portion is smooth and even running; and it requires no machining or other operations to make a perfect uniform character of wheel, when it comes from the dies.

The finish and appearance of the wheel herein disclosed may be made exceptionally and characteristically attractive by deforming the material thereof under dies, which deformation insures greater strength and rigidity to the wheel structure.

The invention of the present application illustrates and describes a wheel somewhat similar to those of co-pending applications, Serial Nos. 566,901, filed June 8, 1922, and 664,417 filed September 24, 1923, which applications have since matured respectively into Patents 1,497,659, dated June 10, 1924 and 1,495,140, dated May 20, 1924; and applications of concurrent date, although the present invention embodies improvements not illustrated, described or claimed in said co-pending applications.

Referring to the drawings:

Figure 1, illustrates the finished wheel in one form, the dotted outline illustrating the spoke section as punched out from the material.

Figure 2, is a section on the line 2—2 of Figure 1.

Figure 3, illustrates a section of a felloe portion completely rolled, and on an enlarged scale.

Figure 4, illustrates the felloe section with smaller offsets than that of Figures 2 and 3, also on an enlarged scale.

Figure 5, illustrates a narrow felloe in comparison with Figs. 1 to 4, inclusive.

Figure 6, shows a modified fastening means between spoke and felloe sections.

Figure 7, is a sectional view, on an enlarged scale, through the junction of the spoke with the felloe of Fig. 6.

The invention, herein described, contemplates the use of a sheet of material having sufficient ductility to permit blanking, shap-

ing, curling and deforming, and yet of sufficient strength to provide a composite structure of great rigidity.

In carrying out the invention, a disc is first blanked out of sheet material and upon submission to the action of suitable dies, its peripheral edge is offset, drawn or curled up to provide the required and desired form of tread or running surface. The blanked disc, so formed, is then deformed as to portions of its surface and pierced to give a central opening for the axle, which opening is, of course, truly concentric with the curled or offset peripheral edge or felloe.

A blanking operation, which cuts out the spoke sections, is next employed, and this operation provides the spokes with hub section and the deformed or stiffening portions of the blank for strengthening the spokes. The operation just referred to produces from a single disk of metal the central hub and spoke section of the wheel and the peripheral felloe section. The central blanked out portion is then placed in the remaining peripheral section and the ends of the spokes are riveted or spot welded to the felloe section in the case of Figs. 1 to 5, inclusive, and in the case of Figs. 6 and 7, the ends of the spoke section are curled directly into the formed up rim or felloe section.

It will be quite obvious, from this series of steps, that a complete wheel is stamped out of a single disc, the spoke and hub portions being cut out of what would ordinarily be scrap, and reunited with the felloe portion.

This method of production gives great latitude in design and finish as the spoke and hub sections may be treated to give any desired colored effect, independent of the color effect which is produced for the tire sections.

Referring to the drawings, numeral 1, indicates the disc, first stamped from a sheet of material and illustrated in its full size by the dotted outline 2, of Fig. 1.

The peripheral edge of the disc 2, is curled or offset to form the felloe 3, Figure 2, illustrating a U-shaped drawing of this rim while Figure 3, shows the rim curled into a circular form. Figure 4, shows a more sharply defined angular offset.

It will be obvious that the formation of the rim section may be of a design and character to meet the exigencies of any particular requirement. Broad flat tires may be secured, of annular like form, or tubular like treads may be produced, as illustrated in Figure 3, or the shorter flat tread of Figure 4, may be secured, all dependent upon the form of the die for producing deformation and drawing of the metal at the peripheral edge of the disc.

It will be apparent from the dotted line of Figure 1, the spoke and hub section of the wheel is blanked out of the disc and the only

loss in metal in scrap, is that indicated by the shaded portions of Figure 1.

The spokes 4, 5, 6, 7, 8, may have any desired form, dependent upon the shape of the dies, but it is preferred to form them with an end having lateral extensions 9, 10, to give a firm hold upon the interiorly extending flange portion 11, of the felloe or tread section of the wheel. The flange 11 is comparatively long and of uniform shape throughout—that is, it is not notched or otherwise deformed.

After the spoke section is blanked out, as indicated, the spider like form of spoke and hub section is applied, to the felloe portion at points intermediate the end cuttings, A, B, C, D, made for the spokes: for instance, as at E, F, G, and H. The ends of the spokes may then be secured to the flange 11, of the felloe, by any suitable means, preferably by spot welding, although it is quite apparent that the parts could be pierced and riveted, if desired. Spot welding, however, obviates any liability of throwing the parts out of true.

As they come from the dies in perfect form, cut with great accuracy, they may be readily spot welded without destroying the accuracy, and this operation gives what is, in effect, a completed wheel of homogeneous material.

In Fig. 5, the flange 11, of Fig. 1, has been cut away, except as to small portions 12, to provide a means of attachment for the ends of the spokes which are, of course, spot welded. This form of device very much reduces the inside and outside diameters of the felloe and effect a great saving in material where the felloe or rim portion of the wheel is covered with a resilient material. For instance, there is a great saving where a cord or chenille is wound about the felloe portion, as indicated at 20, Fig. 1, to give a soft running tread and the appearance of a pneumatic tire.

In Figs. 6 and 7, in place of spot welding the parts, a somewhat deeper cut into the felloe portion is made, when forming the spokes 13, 14, and in this case, the blanking out of the spoke and hub section of the wheel is effected prior to the curling of the edge of the disc.

The blanked out hub and spoke section of spider like form is then revolved approximately 45°, and the curling dies form the ends of the spokes into the recesses of the curled edge of the felloe. This is illustrated in Figs. 6 and 7 where the spoke ends 13, 14, etc., are cut out of the disc 15, and then turned to a point approximately at 16, where they are curled and forced, along with the felloe portion, into a U shape, the felloe portion 17, having a greater peripheral area than that of the U-shaped spoke end 18, which is forced thereinto.

This form of the device gives a very substantial wheel and does not require spot welding or riveting to unite the spoke section and the felloe section.

- 5 In any of the forms of wheels described, or which it is desired to make, the spoke section, as it is punched or blanked out, may be embossed or deformed as at X, to give added stiffness to the spider like spoke section.
- 10 This embossing may, of course, take any desired form, of a more or less artistic character and its effect, mechanically, is always the same, namely, that of stiffening up the spider like spoke section.
- 15 The same result of stiffening is attained by offsetting, curling or rolling up the metal of the felloe portion to provide the tread or tire.
- 20 It is quite obvious that various modifications and the exact form of stamping may be made within the scope of the invention, without departing from the spirit or intent thereof.
- 25 In any case, a comparatively thin material may be used which, when deformed and blanked out, as described, will produce a very

attractive and extremely cheap type of wheel having unusual features of attractiveness and strength.

What I claim as my invention and desire 30 to secure by Letters Patent is:

1. A wheel for toys formed from a disk of metal consisting of a felloe section having a deformed peripheral edge providing a smooth running section or tread and having 35 interiorly thereof, a comparatively long flange of uniform shape throughout, and a spider like spoke section blanked out of the disc and reunited to the flange the ends of the spokes overlapping the flange at points 40 other than those from which they were blanked out.

2. A wheel for toys formed from a disk of metal consisting of a felloe section having a deformed peripheral edge providing a 45 smooth running section or tread and having interiorly thereof, a flange, and a spider like spoke section blanked out of the disc, the ends of the spokes of said section overlapping and being welded to the flange.

CLIFFORD M. WATROUS.
